UNITED STATES PATENT OFFICE.

HENRY GIBSON O'NEILL, OF NEW YORK, N. Y., ASSIGNOR TO CONRAD HUBERT, OF HEWLETT, NEW YORK.

ELECTRICAL ENGINE-STARTING APPARATUS.

1,315,790.

Specification of Letters Patent.

Patented Sept. 9, 1919.

Application filed September 21, 1915, Serial No. 51,757. Renewed April 11, 1919. Serial No. 289,467.

To all whom it may concern:

Be it known that I, HENRY GIBSON O'NEILL, a citizen of the United States of America, residing at borough of Manhattan, 5 in the county of New York and State of New York, have invented certain new and useful Improvements in Electrical Engine-Starting Apparatus, of which the following is a specification, reference being had therein 10 to the accompanying drawings, forming part thereof.

My invention relates to engine-starting apparatus for starting internal combustion engines particularly those of motor cars and 15 relates more particularly to electrically operated engine-starting apparatus. Such apparatus may be divided generally into two types, namely: the single unit type in which a combined dynamo and motor, 20 known in the art as a dynamo-motor, is employed as a dynamo operated by the engine for generating electrical energy which is stored and utilized in the dynamo-motor operated as a motor for cranking the engine; 25 and the two unit type in which a dynamo is employed for generating electrical energy which is stored and utilized in a separate electric motor for cranking the engine. Some of the important features of my 30 invention are equally applicable to both of these types of apparatus, but other features of my invention are more particularly applicable to the single unit or dynamo-motor type of engine-starting apparatus.

One object of my invention is to produce 35 an engine-starting apparatus equally well adapted to be supplied as equipment on new cars or to be applied to motor cars which have been built without provision 40 having been made thereon for an engine starter and in either case without requiring alteration, re-arrangement or disturbance of any vital or important parts of the car as previously built without an engine-starting 45 apparatus; and also to produce an engine-starting apparatus particularly adapted for installation at the front of the car forward of the engine. Another object of my invention is to produce an engine-starting apparatus 50 particularly adapted for light cars, such for example as the Ford motor car. Other objects of my invention are to maintain the balanced condition of the engine and car as to distribution of weight and to 55 assure the unimpeded transmission of power

between the starter shaft and the engine shaft. Other more general objects of my invention are inexpensiveness of manufacture and installation, convenience of installation, simplicity and compactness of construction, durability, reliability, accessibility, coolness of the apparatus in operation, neatness and symmetry of appearance, convenience of use and other objects and advantages which will hereinafter appear. 60 65

In carrying out my present invention I employ an engine-starting apparatus for cranking the engine in which the starting apparatus is combined with the spark advancing and retarding device in such a way 70 that the cranking operation is caused to take place by moving the spark advancing and retarding device to a retarded spark position without interference with the functions of said device; and in this connection 75 my invention includes a relay circuit controller in control of the circuits of an engine-cranking electrical engine starter, such as a dynamo motor, and the control of the circuit of the relay by a master switch which is operated by the spark advancing and retarding device of the engine, the relay also serving to operate a clutch by which the dynamo-motor is connected to the engine 80 85 to crank the engine. My invention further includes features of construction and combinations of parts as will appear from the following description.

I shall now describe the engine-starting apparatus embodying my invention illustrated in the accompanying drawings and shall thereafter point out my invention in claims.

Figure 1 is a vertical longitudinal section of the engine starter shown in attached position on a Ford motor car as viewed 95 from the right side.

Fig. 2 is a transverse section on a plane indicated by the line 2-2 of Fig. 1 as viewed from the left.

Fig. 3 is a similar section indicated by the line 3-3.

Fig. 4 is a partial section on a plane indicated by the diagonal line 4-4 of Fig. 2 as viewed diagonally downward from the 105 right, the casing being omitted, and shows the electrically controlled clutch.

Fig. 5 is a rear elevation of the engine starter in attached position as seen from the left in Fig. 1 and with parts in section. 110

Fig. 6 is a front elevation of the same as viewed from the right in Fig. 1 with the front inclosing cover removed.

Fig. 7 is a plan of the master switch and its immediate connections.

Fig. 8 is a rear elevation of an automatically acting restoring device shown as mounted upon the steering column of the Ford motor car.

10 Fig. 9 is a plan of what appears in Fig. 8.

Fig. 10 is a transverse section on a plane indicated by the line 10—10 of Fig. 8 as viewed from above.

15 Fig. 11 is an elevation as viewed from the left in Figs. 8, 9 and 10, the steering column here appearing in its usual inclined position, together with portions of the steering wheel.

20 Fig. 12 is a diagrammatic representation of the electric circuits, engine-starting apparatus and circuit-controlling devices.

In the electrical equipment embodying my invention illustrated in the accompanying drawings as applied to a Ford motor car, the engine-starting apparatus has its engine-cranking operation initiated by and is wholly controlled and caused to operate by the spark-advancing and retarding device

30 of the motor car engine without any interference with the functions of said device. A clip 1 which constitutes the movable member of a master switch or master circuit controller is shown as securely clamped upon

35 the transversely extending endwise movable operating rod 2 of the usual spark advancing and retarding device so that the switch clip 1 will partake of the movement of the rod or link 2. This link 2 at one of its ends

40 is connected to and operates the usual timing device 3 of the ignition apparatus which may be of the usual or of any suitable construction. At its other end the link 2 is connected for operation to a usual lever arm 4 fixed upon the lower end of the usual rotative controlling shaft 5 which in the Ford motor car, as is well understood, lies alongside of the steering shaft 6, and the upper portion of the spark controlling shaft 5 and

50 steering shaft 6 are inclosed and supported by the steering column or steering post 7. The spark-controlling shaft 5 is provided at its upper end with the usual manually actuatable spark lever 8 which projects just beneath the rim of the steering wheel 9, Fig. 11.

The movable contact clip 1 of the master switch is electrically coöperative with a stationary contact pin 10 which is arranged in 60 the path of the movable contact clip 1 as the latter moves in the direction corresponding to spark retardation, and the movable contact clip 1 is arranged or positioned on the link 2 so that it will engage or come in contact with the stationary contact pin 10 sub-

stantially at the position or condition of maximum spark-retardation. The stationary contact pin 10 is shown as supported by a bracket 11 from which it is electrically insulated by an interposed insulating sleeve 12. The master switch, including the movable contact clip 1 and the stationary contact pin 10, is in control of an electrical device which in turn is in control of both the engine-starting and the energy generating 75 operation of a dynamo-motor, having a rotative armature 13 and a stationary field 14 shown as compound wound as appears in diagram in Fig. 12. As appears in Fig. 12 the electric circuits are of the single wire or 80 grounded type the frame of the motor car serving as a common return conductor as is well understood.

The above mentioned electrical controlling device, appearing in Figs. 2, 4 and 12 85 of the drawings, comprises a solenoid 15 having a magnetic field frame or yoke 16 and a movable magnetic core or plunger 17 which is retracted by a coiled thrust spring 18. This electrical controlling device includes a relay or electrically operated circuit controller and also includes electrically operated clutching means, the relay circuit controller being in control of the dynamo or generating circuit and being also in control 90 of the motor circuit of the dynamo-motor 13—14, and the electrically operated clutching means being in control of speed-reducing gearing to render such gearing operative when the dynamo-motor 13—14 operates as 95 a motor in effecting an engine-cranking operation.

At its outer or projecting end beyond the thrust spring 18 the solenoid plunger 17 carries a switch blade 19 which is insulated 105 from the plunger 17 as indicated in the drawings and which is shown as of a compound or leaf construction as is well understood in the art. When the solenoid plunger 17 is in the retracted position corresponding 110 to the deenergized condition of the solenoid coil 15, this being the position indicated in the drawings, of which see Figs. 2 and 12 particularly, the switch blade 19 will make an electrical connection between a pair of 115 stationary contact plates 20 mounted upon but insulated from a switch base or supporting plate 21 which in turn is supported on the magnet frame 16, these contact members or contact plates 20 being included in the 120 generating circuit of the dynamo-motor 13—14 as will presently appear. In the other or drawn-in position of the plunger 17, corresponding to the energized condition of the coil 15, the switch blade 19 is coöperative 125 with and will make an electrical connection between a pair of stationary contact blocks 22 also supported upon and insulated from the base plate 21, and insulated also from the contact plates 20, the contact blocks 22 form-

100

ing a part of the motor circuit of the dynamo-motor 13—14.

The movable magnetic core or plunger 17 is provided at its other end opposite to the switch blade 19 with a rigidly projecting non-magnetic tubular extension or connecting rod 23 for operating a clutch pawl 24. The pawl 24 is pivoted upon a bearing pin 25 supported in flanged attaching portions of the magnet yoke or frame 16. The clutch pawl 24 is moved to the engaging position by the rigid tubular connecting rod 23 through the intermediary of a substantially U-shaped clip or yoke 26 and an interposed coiled spring 27 which forms a resilient yielding connection, and the pawl 24 is moved to the free or disengaged position directly by the clip 26 which is pivoted on the bearing pin 25 and has a free projecting end which enters a hole or opening in one side of the connecting rod 23 as shown in the drawings, Figs. 2 and 4. The pawl 24 is engageable with the peripheral ratchet teeth of a combined gear ring and ratchet ring 28 for mechanically connecting the dynamo-motor 13—14 with the engine for operation as a motor to effect an engine-starting operation by cranking the engine through speed-reducing gearing as hereinbefore mentioned and as will presently be explained.

The electric circuits of the apparatus will now be traced reference being had more particularly to Fig. 12 where the electric circuits are shown as of the single wire or grounded type, the frame of the motor car serving as a common return conductor as is well understood. A storage battery 29 is employed and the generating or battery-charging circuit from the dynamo-motor 13—14 operated as a dynamo to the storage battery 29 includes a conductor 30, the upper or left contact block 22, a conductor 31, a current regulating device 32, a conductor 33, the lower or right contact block 22 and a main or line conductor 34 to the battery 29, this being the armature and series field circuit of the dynamo-motor operated as a generator and of which the shunt field circuit includes a conductor 35, the upper or left contact plate 20, the switch blade 19, the lower or right contact plate 20, a conductor 36 and the current regulating device 32 to the conductor 33.

The electric circuit from the storage battery 29 to the dynamo-motor 13—14 operated as an engine-starting motor for cranking the engine is through the line conductor 34, the contact block 22 at the right, the switch blade 19, the contact block 22 at the left, and the conductor 30 to the series field and through the armature 30 to ground, the circuit which includes the shunt field 14 and the regulating device 32 now being open. This engine-starting condition of the circuit is produced by the energizing of the

coil 15 by reason of which the switch blade 19 is moved out of contact with the contact plates 20 and into contact or engagement with the contact blocks 22. The energizing circuit of the coil 15 includes a conductor 37 shown as tapped onto or connected with the battery or line conductor 34, and a conductor 38 which is connected to the stationary contact pin 10 of the master switch hereinbefore described. The movable contact clip 1 has a grounded connection through the operating link 2 and other metal parts of the car and is coöperative with the contact pin 10 to close or to open the circuit of the magnet coil 15.

The current regulator 32 is connected in the generating circuit in the usual way as is indicated in Fig. 12 and may be of any suitable construction this current regulator being illustrated diagrammatically in Fig. 12 and shown in outline in Figs. 1 and 2. As is well understood in the art the current regulator 32 controls the charging of the storage battery 29 and also prevents discharge of the battery through the generator circuit. A lighting circuit 39 is shown as connected to the main conductor 34 in multiple relation with the battery 29 and generating circuit of the dynamo-motor 13—14.

It will now be understood that when the spark lever 8 is moved in a clockwise direction, as viewed in Figs. 9 and 12, to the position of maximum spark-retardation the movable contact clip 1 carried by the timer operating link 2 will be brought into engagement with the stationary contact pin 10 thereby closing the circuit of and energizing the solenoid 15. The energized solenoid 15 opens the generator circuit by moving the switch blade 19 away from the contact plate 20 and closes the motor circuit by bringing the switch blade 19 into contact with the contact blocks 22 and also moves the clutch pawl 24 into engagement with the ratchet teeth of the combined ratchet ring and gear ring 28 so that concurrently the dynamo-motor 13—14 will be operated as a motor and will be mechanically connected with the engine to crank the engine, and without any interference with the functions of the spark advancing and retarding device of the engine. As soon as the spark lever 8 is moved away from the position of maximum spark-retardation toward a position of more advanced spark, the contact clip 1 will be moved away from the contact pin 10 and the energizing circuit of the coil 15 will be opened. When the solenoid 15 is deenergized its plunger 17 will be retracted by the thrust spring 18 and the switch blade 19 will be moved to open the motor circuit at the contact posts 22 and to close the generating circuit at the contact plates 20. Also at the same time the clutch pawl 24 will be moved clear of the ratchet teeth of the com-

bined ratchet ring and gear ring 28 so that it will not rattle or knock against these teeth by reason of the rotation of the gear ring 28 during the operation of the dynamo-motor 13-14 as a generator.

For convenience of operation and to avoid unnecessary drains upon the battery 29 by reason of the spark lever 8 being accidentally moved to or inadvertently left at the 10 engine-starting position, an automatically acting device is provided for moving the spark lever 8 away from the position of combined maximum spark-retardation and engine-starting operation of the dynamo-motor 13-14. This automatically acting restoring device is shown in the drawings as a spring actuated device mounted on the upper end of the steering column 7 in the path of the spark lever 8 as it is moved toward the position of maximum spark-retardation and engine-starting operation. A spark lever restoring lever arm 40 is pivoted by means of a pivot stud 41 on a split supporting bracket 42 which is clamped upon the upper end of the steering column 7 just below the usual double quadrant 43 for the spark lever 8 and usual throttle lever, as shown. The spring-pressed lever arm 40 projects upward in the path of the spark lever 8 just at the outside of the spark lever portion of the double quadrant 43 and just in advance of the usual abutment stop or projection shown as formed thereon for arresting the further movement of the spark lever 8 at the position of maximum spark-retardation. The end of the clamp bracket 42 projects and is turned over as shown in the drawings so as to form a forward stop for the spring-pressed lever arm 40 which is pressed toward the spark lever 8 by a torsional spring 44 coiled about the pivot stud 41 as shown. The position of the upper end of the lever arm 40 in the path of the spark lever 8 is such that the movable contact clip 1 will not be brought into engagement with the stationary contact stud 10 until after the lever arm 40 has been pushed back against the tension of its spring 44, the arrangement preferably being such that the 50 contact clip 1 engages the contact pin 10 just before the spark lever 8 engages the abutment stop formed on the quadrant 43. To start the engine the driver moves the spark lever 8 to the usual position of maximum spark-retardation and then holds the spark lever in this combined spark-retarding and engine-starting position until the engine starts after which he removes his hand from the spark lever and the dynamo-motor 13-14 will then be automatically converted from a motor to a generator by reason of the pushing forward of the spark lever 8 by the lever arm 40 under the actuation of its spring 44.

65 All of the electrical and mechanical parts

of the starter mechanism are contained within an inclosing casing forming a compact unitary construction. Such inclosed parts include those of the dynamo-motor 13-14, the set of reducing gears therefor, the electrically operated circuit controller for the dynamo-motor, the electrically operated clutching means for the gearing, the electrical operating means for such controller and clutching means, and the current regulator 70 75 80 85 90 95 100 105 110 115 120 125 130 32. The inclosing casing is shown as made up of a magnetic cylindrical shell or field frame 45, a front yoke or frame 46 and a rear housing 47. Also a front cover 48 having a central screw cap 49 is provided, and there is also provided a rear cover plate 50 for an opening in the lower part of the housing 47 which latter extends downward for some distance below the field frame 45, as clearly appears in the drawings, thereby to provide space for the electrical controlling devices including the solenoid 15 and its adjuncts and the current regulator 32, the solenoid 15 being mounted in an inclined position below and at the right as viewed from the rear of the starter and the current regulator 32 occupies a similar position at the left.

Returning now to the actuating or operating parts of the engine-starting apparatus, it will be noted as hereinbefore described, that one of the results of the energizing of the solenoid 15 in the engine-starting operation is the movement of the electrically operated clutch pawl 24 into engagement with the peripheral ratchet teeth of the gear ring 28. During an engine-starting operation the gear ring 28 will have imparted to it a clockwise torque impulse as viewed from the rear of the starter mechanism, which will be as appears in Fig. 2 and as viewed from the left in Fig. 1, such torque impulse of the ring 28 being in a direction opposite to that of the rotation of the engine shaft. The pawl 24 by its engagement with the ratchet teeth of the ring 28 forms an abutment which prevents the above noted clockwise rotation of this ring and holds it stationary, so that this gear ring 28 forms an abutment gear. The ring 28 is shown as supported upon a two-part gearing carrier 51 the two parts of which are firmly secured together by means of four rivets 52 and two dowel pins 53 as appears in Fig. 2. The gearing carrier 51 is mounted to rotate relatively to the ring 28 and carries a pair of planetary spur pinions 54 journaled by means of bushings as shown on bearing pins 55 and meshing with internal gear teeth formed on the gear ring 28.

A sleeve 56 forms a hollow or tubular armature shaft for the armature 13 of the dynamo-motor and has gear teeth thereon at its rear end forming a pinion which engages with the planetary pinions 54. The arma-

tire-carrying sleeve 56 is loosely journaled upon an engine-connected starter shaft 57. The starter shaft 57 is journaled in front and rear bearings in the front yoke 46 and 5 rear housing 47, respectively, of the inclosing casing and projects rearward beyond its rear bearing for connection to the engine shaft and projects forward beyond its front bearing for the application of a crank for 10 starting the engine manually should the starting apparatus get out of order. In the engine-starting operation power for cranking the engine is taken from the gearing carrier 51 which has, as shown, a rearwardly projecting hub which is fixed upon the engine-connected starter shaft 57. The starter shaft 57 is in alinement with and is rotatively coupled to the engine shaft 58 by 15 means of a short intermediate coupling shaft 59 and a spring-pressed coupling sleeve 60 the spring 61 for which surrounds the coupling shaft 59, Fig. 1. The coupling shaft 59 and coupling sleeve 60 form a flexible floating driving or power-transmitting connection between the starter shaft 57 and the engine shaft 58 thereby assuring smoothness of running and the efficient transmission of power.

It will now be readily understood, with 20 the combined gear ring and ratchet ring 28 held by the electrically controlled pawl 24 against clockwise rotation as viewed from the rear, that counter-clockwise rotation of the tubular armature shaft 56 will impart 25 rotation in the same or counter-clockwise direction at a reduced rate to the gearing carrier 51 and engine connected starter shaft 57 through the planetary pinion 54, the ring 28 being stationary and serving as an abutment gear. In the construction illustrated 30 in the drawings, the rate of speed reduction thus effected through the planetary gearing from the armature-carrying sleeve 56 to the engine-connected starter shaft 57, which of 35 course rotates at engine speed, is about one rotation of the starter shaft 57 to a little more than six and one-half rotations of the tubular armature shaft 56, but it is understood of course that the rate of reduction 40 may be varied by varying the relative dimensions of the several parts of the planetary gearing.

In the energy-generating operation of the 45 dynamo-motor the dynamo-motor is driven directly from the engine at engine speed without the operation of the planetary gearing. For this purpose the gearing carrier 51 is connected directly to the tubular armature shaft 56 by means of an automatically 50 acting unidirectional clutch comprising an inner clutch member or toothed clutch cam 62 fixed upon a forwardly projecting hub or sleeve portion of the forward part of the two-part gearing carrier 61, and an outer 55 flanged clutch member or clutch ring 63

which is fixed upon the armature sleeve 56, gripping rollers or clutch rollers 64 being interposed between the clutch members 62 and 63. It will now be readily understood that when the engine is the driver the combined ratchet and gear ring 28 rotates with the gearing carrier 51 and that the gearing carrier 51 is clutched to the armature sleeve 56 so that the latter is driven directly from the engine-connected starter shaft 57 at engine speed without the operation of the planetary gearing which now rotates as a whole without relative movement of its parts, so that in its energy generating operation the dynamo-motor 13—14 will be operated as a direct connected dynamo without any frictional drag or load such as would be caused by intermediary gearing particularly by multiplying gearing such as is commonly employed.

The inclosing casing with its contained starter mechanism is supported at the front of the car forward of the engine by means of triangularly arranged three-point supports of a construction now to be described. 85 A sheet metal supporting bracket 65, appearing in Figs. 1 and 5, is of generally triangular shape and is provided, as shown, at its upper and wider end with a pair of upwardly and forwardly projecting attaching lugs which are received in recesses or depressions formed in the rear housing part 47 of the casing at each side thereof above the starter shaft 57, and this supporting bracket at its lower end has a supporting 90 lip turned forward beneath the housing 47, the two lugs and the lower end portion of the supporting bracket 65 being fixed to the housing 47 by means of tap bolts as shown. This supporting bracket 65 is provided as 95 shown with rearwardly projecting flanges just below and inward from the above mentioned attaching lugs thereof and at each side of the starter shaft 57. These supporting flanges of the bracket 65 are firmly secured to the cross frame 66 of the Ford car by means of the U-bolts or shackles 67 which are commonly employed upon Ford cars for holding the frame piece 66 to the front 100 spring of the car. In its lower portion the 105 supporting bracket 65 is shown as provided with rearwardly projecting side flanges and has near its lower end a pair of spaced ears as shown. A brace rod or strut 68 has a head or clevis 69 pivoted between the bracket 110 ears by a pin 70 and extends substantially horizontally rearward and at its rear end passes through a flanged rib 71 on the bottom of the engine crank case 72 and is firmly held in place by nuts at opposite sides of 115 the rib 71 as clearly appears in Fig. 1. The three triangularly arranged supports such as above described firmly hold the starter mechanism so that it will not be disarranged by 120 jars or vibration and assure maintenance of 125 130

alinement of the starter shaft 57, the coupling shaft 59 and the engine shaft 58.

It should be noted that the starter mechanism is shown as supported on the car entirely from the rear housing 47 of the inclosing casing and that the field frame 45 and the front frame part 46 are supported on the housing 47 by means of two upper longer bolts 73 and two lower shorter bolts 74 all of which have their heads exposed at the front beneath the front cover 48 as appears most clearly in Figs. 1 and 6. It is to be further noted that the electrical controlling devices, such as the current regulator 32 and the solenoid 15 and its adjuncts, are supported on and carried by the rear housing 47 and also that the commutator and brushes of the dynamo-motor are at the front, the brush holders 75 being mounted upon the front frame part or yoke 46, as shown in Figs. 1 and 6. By reason of the arrangement just described the entire armature 13 and also the gearing may be detached and removed for inspection or repairs without removing the housing part 47 from the car and also without in any manner disturbing the wiring or conductive connections, it being merely necessary to remove the front cover 48 and the bolts 73 and 74. The commutator and brushes, which may be of any suitable construction, are accessible merely by removing the front cover 48.

It is obvious that various modifications may be made in the construction shown in the drawings and above particularly described within the principle and scope of my invention.

I claim:

1. An electrical engine-starting apparatus for an internal combustion engine combined with the spark advancing and retarding device of the engine and comprising an electric motor for cranking the engine, and circuit controlling means for the motor controlled by the spark advancing and retarding device without interference with the functions of said device and arranged to close the motor circuit for cranking the engine upon the movement of said device to a retarded spark position and to open the engine-cranking motor circuit upon the movement of said device to a more advanced spark position; said circuit controlling means including a relay circuit controller for closing or opening the engine-cranking circuit of the motor, and a master switch

operated by the spark advancing and retarding device in control of the circuit of the relay circuit controller.

2. An electrical engine-starting apparatus for an internal combustion engine combined with the spark advancing and retarding device of the engine and comprising a dynamo-motor for cranking the engine when operating as a motor and for operating as a generator when driven by the engine, and circuit controlling means for the dynamo-motor controlled by said device to open the generator circuit and close the motor circuit for cranking the engine upon the movement of said device to a retarded spark position and to open the engine-cranking motor circuit and to close the generator circuit upon the movement of said device to a more advanced spark position, without interference with the functions of said device; said circuit controlling means including a relay circuit controller in control of the circuits of the dynamo-motor, and a master switch operated by the spark advancing and retarding device in control of the circuit of the relay circuit controller.

3. An electrical engine-starting apparatus for an internal combustion engine combined with the spark advancing and retarding device of the engine and comprising a dynamo-motor for cranking the engine when operating as a motor and for operating as a generator when driven by the engine, and circuit controlling means for the dynamo-motor controlled by said device to open the generator circuit and close the motor circuit for cranking the engine upon the movement of said device to a retarded spark position and to open the engine-cranking motor circuit and to close the generator circuit upon the movement of said device to a more advanced spark position, without interference with the functions of said device; said circuit controlling means including a relay circuit controller in control of the circuits of the dynamo-motor, and a master switch operated by the spark advancing and retarding device in control of the circuit of the relay circuit controller; and a clutch operated by the relay circuit controller for connecting the dynamo-motor to the engine to crank the engine.

In testimony whereof I have affixed my signature.

HENRY GIBSON O'NEILL.
